D11-160. OR D21,787 EX

DESIGN.

C. HOLLOWAY.

STATUE.

No. 21,787.

Patented Aug. 23, 1892.

Witnesses
W. G. Corlies
John W. Adams

Inventor
Charles Holloway,
By E. Crawford Atty

UNITED STATES PATENT OFFICE.

CHARLES HOLLOWAY, OF CHICAGO, ASSIGNOR TO LOUIS H. AYMÉ, OF LA GRANGE, ILLINOIS.

DESIGN FOR A STATUE.

SPECIFICATION forming part of Design No. 21,787, dated August 23, 1892.

Application filed July 11, 1892. Serial No. 439,704. Term of patent 14 years.

To all whom it may concern:

Be it known that I, CHARLES HOLLOWAY, a citizen of the United States, residing in Chicago, in the county of Cook, State of Illinois, have invented and produced a new and original Design for a Statue, which shall be typical of the city of Chicago, Illinois, of which the following is a specification, reference being had to the accompanying drawing, showing the front view thereof.

The figure shown in the drawing is the front view of the statue in erect position, and it is deemed sufficient to fully illustrate my design.

The leading features of my design are as follows, viz: The figure of a young woman, strong, vigorous, and self-reliant, standing erect, facing the observer. Her feet are shod with moccasins, intended to suggest the city's beginning in the midst of Indians in their primitive state. Her body is clad in a loose tunic, suggesting freedom of action. Her right arm bears a strap just above the wrist, such as laborers wear to strengthen the wrist and hand for performing the hardest labor. Her right hand rests firmly against the hip. Her left hand holds a builder's square, showing that all her work is tried and proved correct. On her breast she wears a corslet. Except the strap above named, the arms are bare and are shown as having the fullest muscular development consistent with womanly grace. Her hair is short and free. She wears a head-dress consisting of the representation of the fabled phenix rising out of the flames, designed to typify the city rising again from the great fire which destroyed it. The poise of the head and expression of the face are designed to indicate courage and confidence. The whole figure is intended to typify Chicago in its past, present, and future.

What I claim is—

The design for the statue, herein shown and described.

CHARLES HOLLOWAY.

Witnesses:

LOUIS H. AYMÉ,
E. C. CRAWFORD.